Andrew W. Chu(57) **CLAIM**

The ornamental design for a pan lifter, as shown and described.

DESCRIPTION

FIG. 1 is an upper perspective view of a pan lifter showing my design;

FIG. 2 is a top plan view thereof;

FIG. 3 is a bottom plan view thereof;

FIG. 4 is a side elevation view thereof;

FIG. 5 is an opposite side elevation view thereof;

FIG. 6 is an end elevation view thereof;

FIG. 7 is an opposite end elevation view thereof; and,

FIG. 8 is another upper perspective view thereof.

The pan lifter is a handheld device for use in the kitchen.
